(57) **CLAIM**

The ornamental design for a mobile radiant heater, as shown and described.

DESCRIPTION

FIG. 1 is a perspective view of a mobile radiant heater showing the design of this invention.

FIG. 2 is a front view.

FIG. 3 is a top view thereof.

FIG. 4 is a right side view thereof.

FIG. 5 is a left side view thereof.

FIG. 6 is a rear view thereof; and,

FIG. 7 is a bottom view thereof.
